CLAIM

The ornamental design for an ornament, as shown and described.

DESCRIPTION

FIG. 1 illustrates a top perspective view of an ornament, showing our new design;

FIG. 2 illustrates a left-side view thereof;

FIG. 3 illustrates a right-side view thereof;

FIG. 4 illustrates a top view thereof;

FIG. 5 illustrates a bottom view thereof;

FIG. 6 illustrates a front view thereof; and,

FIG. 7 illustrates a back view thereof.

The broken lines in the figures depict portions of the ornament that form no part of the claimed design.

1 Claim, 2 Drawing Sheets
